US00D757449S

(12) **United States Design Patent**
Zeamer

(10) **Patent No.:** **US D757,449 S**
(b4) **Date of Patent:** **** May 31, 2016**

(54) **FLOOR PANEL WITH WOODGRAIN PATTERN**

(71) Applicant: **Armstrong World Industries, Inc.,**
Lancaster, PA (US)

(72) Inventor: **Mark C. Zeamer**, Columbia, PA (US)

(73) Assignee: **ARMSTRONG WORLD INDUSTRIES, INC.**, Lancaster, PA (US)

(**) Term: **14 Years**

(21) Appl. No.: **29/480,427**

(22) Filed: **Jan. 26, 2014**

(51) **LOC (10) Cl.** **06-06**

(57) **CLAIM**

The ornamental design for a floor panel with woodgrain pattern, as shown and described.

DESCRIPTION

The sole FIGURE is a plan view of a floor panel with woodgrain pattern showing my new design.

The broken line perimeter surrounding the floor panel with woodgrain pattern depicts the boundary of the panel and forms no part of the claim.

1 Claim, 1 Drawing Sheet
